UNITED STATES PATENT OFFICE.

SILAS S. PUTNAM, JR., OF BOSTON, MASSACHUSETTS, ASSIGNOR OF ONE-HALF
TO WILLIAM W. WHITMARSH, OF SAME PLACE.

SELF-ADJUSTING FENDER OR GUARD FOR RAILWAY-CARS.

SPECIFICATION forming part of Letters Patent No. 431,393, dated July 1, 1890.

Application filed March 28, 1890. Serial No. 345,742. (No model.)

To all whom it may concern:

Be it known that I, SILAS S. PUTNAM, Jr., a citizen of the United States, residing at Boston, in the county of Suffolk and State of Massachusetts, have invented a Self-Adjusting Fender or Guard for Railway-Cars, of which the following is a full, clear, and exact description, reference being had to the accompanying drawings, making part of this specification, in which—

Figure 1 is a perspective view of a street-railway car having my improved self-adjusting fenders or guards applied to the ends thereof. Fig. 2 is a plan view of the under side of one end of the same. Fig. 3 is a longitudinal vertical section on the line $x-x$ of Fig. 2. Fig. 4 is a vertical section on the line $y-y$ of Fig. 2.

My invention relates particularly to fenders or guards for street-railway cars propelled by electric or other motors where an ordinary fender rigidly or solidly secured to the front of the car cannot be used to advantage, for the reason that when said fender is placed as near to the track as is desirable to avoid accidents the longitudinal rocking or jolting motion of the car will cause it to strike the ground and thereby become injured or broken, while if placed at a sufficient height above the ground to avoid liability of contact therewith it will not answer the purpose for which it is intended. To overcome this difficulty is the object of my invention, which consists in the combination, with a railway-car, of a self-adjusting fender or guard adapted to rock or oscillate on its pivots toward or from the ground independently of the car to which it is attached, means for holding said fender at the proper level and automatically returning it to its normal position after being rocked or oscillated, and an adjustable stop for limiting the downwardly-rocking movement of the fender, as hereinafter set forth.

In the said drawings, A represents the front portion of a railway-car, from the under side of which project two horizontal supporting-bars B B, carrying a transverse shaft or bar C, to the opposite ends of which is pivoted the fender D, preferably composed of sheet metal, and of any suitable or desirable form,

The bolts $a a$, upon which the fender D is hung, pass through suitable apertures in its sides and enter the ends of the bar C, the fender being supported with its lower edge quite close to the ground, and being free to rock or oscillate upon its pivots $a a$ either downwardly or upwardly. The pivots $a a$ are so placed that the fender will swing downward by its own weight to its proper level, in which position it is supported by a spring b, coiled around and fastened to the bar C, whereby if the fender is depressed or rocked downward by encountering an obstruction it will be instantly returned to its original position when released. 65

$d d$ are two bars, which are attached to the under side of the supporting-bars B B by means of screws e passing through slots f, whereby they are made adjustable longitudinally, the outer ends of the bars d serving as stops to limit the rocking movement of the fender when depressed, and these stops are preferably so adjusted that the fender will not come into contact therewith until its front edge touches the ground. In case, however, 75 the fender is brought into contact with the ground by the excessive jolting or longitudinal rocking motion of the car, it will readily yield or rock upward on its pivots $a a$, and be instantly returned to its proper level by 80 its own weight as the end of the car to which it is attached rises, thus avoiding any liability of breakage or injury to the parts, as would occur if the fender were rigidly attached to the car. The spring b may be of any suitable 85 form or description, and, if desired, the fender may be provided with a spring or springs adapted to return it to its proper level when rocked either upward or downward, instead of hanging it so that one portion will over- 90 balance the other.

In order to prevent the front edge 10 of the fender, if brought down upon the ground, from catching under a stone or other obstruction, which might cause it to buckle up or become bent or broken, I provide the fender on its under side near the front edge with a curved or crescent-shaped flange g, the inner edge 15 of which is slightly below the level of the said front edge 10, whereby the latter is 100

prevented from actually striking the ground, the edge of the guard *g* receiving the blow and sliding along the ground, thus preventing any possibility of accident from this cause.

5 If desired, the flange *g* may be dispensed with and the front edge of the fender provided with one or more anti-friction rolls, which would answer the same purpose to prevent the front edge 10 of the fender from 10 catching under any slight projection or obstruction in the road.

It will be obvious that in case the fender should strike a person on the track it will 15 instantly rock or oscillate downward on its pivots against the resistance of the spring *b*, thus materially lessening the shock of the collision and bringing its front edge 10 so close to the ground that nothing can get beneath it, while the rounded form of the fender, combined with its tendency to spring upward and 20 regain its normal position or level, will cause the person to be thrown off to one side clear of the wheels, thus reducing the liability of injury to the person to a minimum, while, as 25 before stated, if the fender is brought forcibly into contact with the ground by the sudden jolting or rocking of the car it will yield, and all liability of breakage from this cause be avoided, advantages not possessed by any 30 guard or fender hitherto constructed with which I am acquainted, and which render my invention especially well adapted for use in

the motor street-cars now commonly used, which, on account of the high speed at which they are run, are the cause of many accidents 35 to life and limb.

What I claim as my invention, and desire to secure by Letters Patent, is—

1. The combination, with a railway-car, of a self-adjusting fender or guard adapted to 40 rock or oscillate on its pivots toward or from the ground independently of the car to which it is attached, means for holding said fender at the proper level and automatically returning it to its normal position after being rocked 45 or oscillated, and an adjustable stop for limiting the downward rocking movement of the fender, substantially as set forth.

2. The combination, with the fender pivoted, as described, and adapted to rock or oscillate toward or from the ground independently of the car to which it is attached, of the flange or guard *g*, secured to its under side near the front edge and extending rearwardly and downwardly below the level of said front 55 edge, substantially as and for the purpose set forth.

Witness my hand this 26th day of March, A. D. 1890.

SILAS S. PUTNAM, JR.
